US00D726680S

(12) **United States Design Patent**
Kim et al.

(10) **Patent No.:** **US D726,680 S**
(45) **Date of Patent:** **** Apr. 14, 2015**

(54) **MOBILE PHONE**

(71) Applicant: **LG Electronics Inc.**, Seoul (KR)

(72) Inventors: **Dongsoon Kim**, Yongin-si (KR);
Hyunwoo Yoo, Seoul (KR)

(73) Assignee: **LG Electronics Inc.**, Seoul (KR)

(**) Term: **14 Years**

(21) Appl. No.: **29/483,218**

(22) Filed: **Feb. 26, 2014**

(30) **Foreign Application Priority Data**

Aug. 27, 2013 (KR) 30-2013-0043929

(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a reference view showing the usage of the subject design in which the subject design has been attached to the watch band; and,

FIG. 9 is a reference view showing the usage of the subject design in which the subject design has been attached to the clip with a strap.

The broken lines in FIGS. 8 and 9 showing the watch band and the clip with a strap depict environmental subject matter and form not part of the claimed design while all other broken lines depict portions of the mobile phone that form no part of the claimed design.

1 Claim, 9 Drawing Sheets
